(57) CLAIM

The ornamental design for a ham bone shaped dog treat, as
shown and described.

DESCRIPTION

FIG. 1 is a top plan view of a ham bone shaped dog treat
showing my new design, the bottom plan view being a
mirror image; and,

FIG. 2 is a side perspective view of FIG. 1, the opposite side
being substantially the same, the only differences being the
dimensions and contours of the simulated meat and fat,
which follow the dimensions and contours thereof shown in
FIG. 1.
